UNITED STATES PATENT OFFICE

151,877

DESIGN FOR A LAMP STANDARD OR SIMILAR ARTICLE

Darrett S. Erwin, Sarasota, Fla.

Application August 23, 1947, Serial No. 141,036

Term of patent 7 years

(Cl. D48—20)

To all whom it may concern:

Be it known that I, Darrett S. Erwin, a citizen of the United States, residing at Sarasota, in the county of Sarasota, State of Florida, have invented a new, original, and ornamental Design for a Lamp Standard or Similar Article, of which the following is a specification, reference being had to the accompanying drawing, forming part thereof, in which the figure is a side elevational view of a lamp standard showing my new design.

The lamp standard has substantially the same configuration on all sides as shown by the drawing.

I claim:

The ornamental design for a lamp standard or similar article, as shown and described.

DARRETT S. ERWIN.
